UNITED STATES PATENT OFFICE.

EWING M. FORBES, OF CHICAGO, ILLINOIS.

FLASHING.

1,051,570.

Specification of Letters Patent. Patented Jan. 28, 1913.

Application filed May 16, 1912. Serial No. 697,647.

To all whom it may concern:

Be it known that I, EWING M. FORBES, a citizen of the United States, residing at Chicago, in the county of Cook and State 5 of Illinois, have invented certain new and useful Improvements in Flashings, of which the following is a specification.

My invention relates in general to the construction of roofs and more particularly 10 to improvements in roof flashings.

Considerable difficulty is experienced in so connecting roofs with adjacent upwardly projecting walls, chimneys, sky-lights, etc., as to secure a permanent water-proof union. 15 This has proved particularly difficult in the case of roofs composed of felt or similar flexible fabrics.

The primary object of my invention is to provide an improved flashing by means of 20 which a water-proof connection may be made between a roof and adjacent wall in a convenient and efficient manner.

A further object of my invention is to provide a roof flashing which will be simple 25 in construction, inexpensive in manufacture, and durable in use.

My invention will be more fully disclosed hereinafter with reference to the accompanying drawings, in which the same is 30 illustrated as embodied in a convenient and practical form, and in which—

Figure 1 is an elevational view showing my improved flashing in position, the roof being shown in section; Fig. 2 a view similar 35 to Fig. 1 showing my flashing applied to a different form of roof; Fig. 3 an enlarged vertical section through my improved flashing, the adjacent portions of the roof and wall being shown; Fig. 4 an elevational 40 view looking toward the left in Fig. 3; Fig. 5 an elevational view showing the flashing arranged for use in two different horizontal planes; Fig. 6 an enlarged sectional view of a joint between adjacent sections of the 45 flashing. Fig. 7 a plan view of the clamp and a portion of its supporting bracket; Fig. 8 a sectional view on line 8, 8, Fig. 7; and Fig. 9 a plan view of the end of the bracket which supports the clamp.

Similar reference characters are used to 50 designate similar parts in the several figures of the drawings.

Reference letter A, referring particularly 55 to Fig. 1, designates a brick wall projecting above the roof support B.

C indicates the roofing material, such for instance as felt or similar roofing fabric.

D designates the outer apron of my improved flashing which overlies the upper edge of the upturned portion of the roofing 60 material C.

E, E designate clamps spaced predetermined distances apart which serve to force the flexible apron of the flashing inwardly 65 against the underlying portion of the roof- ing material.

In Fig. 2 A' designates the wall which projects above the gable roof B', while C' designates the roofing material which extends upwardly adjacent the wall and underlies the pliable apron D of the flashing. 70 The clamps E are located at different levels so as to securely retain the apron of the flashing in close contact with the underlying roofing material. 75

The details of the construction of my improved flashing are more clearly shown in Figs. 3 and 4. F designates the backing of flashing which may be formed of any suitable material, preferably stiff, such as 80 galvanized sheet iron. The backing F is formed of a horizontal portion f' adapted to be inserted between adjacent horizontal rows of bricks, and a depending vertical portion adapted to overlie the lower rows 85 of bricks. The horizontal portion of the backing is preferably folded upon itself so as to receive between the members thereof the upper horizontal portion of the pliable 90 apron, which is preferably formed of sheet lead.

The horizontal portion of the backing F is secured to a bracket G by any suitable means, such for instance as rivets f, one of 95 which may also pass through the inclosed portion of the apron and thereby secure the same to the backing and to the bracket. The front end of the bracket is provided with a depending portion G' through which extends a clamp screw H, which engages 100 the clamping member E and forces the same against the pliable apron D, thereby clamping the roofing material C between the same and the backing F.

Any suitable means may be provided for 105 pivotally supporting the upper end of the clamp E upon the bracket G, such for instance as shown in detail in Figs. 7, 8 and 9, in which a T-shaped opening is formed 110 in the end of the bracket G through which

- detachably extends a projection on the upper end of the clamp. The head or projection e' is of a length to pass through the widest portion g' in the slot of the bracket, 5 while the neck e , which connects the head e' with the clamp E, is of a width to pass within the restricted portion g of the slot so that the head will overlie the side edges of the portion g of the slot and thereby support the clamp upon the bracket. A plurality of such clamps are provided spaced sufficiently close together to insure the proper engagement of the flashing with the roofing material.
- 15 A triangular filler strip of wood K is preferably located in the angle between the support B and the upwardly projecting wall A, as shown in Fig. 3, so as to avoid a sharp bend in the roofing material C where it 20 extends from the roof support upwardly along the wall into engagement with the flashing.

In Fig. 5 I have shown in detail the arrangement of the flashing between sections 25 which lie in different horizontal planes. As will be evident in Figs. 1 and 2 the sloping character of the roof necessitates the flashing occupying different horizontal planes, and hence a portion thereof will be 30 inserted between two horizontal rows of bricks, while an adjacent portion will be inserted between two other horizontal rows of bricks at a lower or higher level, according to the inclination of the roof. In Fig. 35 5 F indicates the backing to which is secured the pliable apron D to be inserted at one plane and from which depends a vertical portion F' of the backing to which is secured a vertical portion D' of the apron. 40 From the lower end of the vertical portion F' of the backing there extends a horizontal portion F^2 to which is secured a horizontal portion D^2 of the apron. In order to insure water-tight joints between the 45 horizontal and vertical portions of the flashing overlapping ears are formed on the connected sections of the apron such as d , d' , d^2 , which are secured within the folded portions of the sections of the flashing by rivets.

50 The manner of using my improved flashing will be readily understood from the foregoing description.

A section of the flashing is placed along 55 a row of bricks above the roof support and a superimposed row of bricks is then placed upon the horizontal portion of the flashing, as will be evident from Figs. 3 and 4. The brackets G are in a similar manner supported between adjacent rows of brick in 60 the wall projecting above the roof. When the roofing material C is laid on the roof support B, the edge thereof adjacent the wall is inserted between the backing F and pliable apron D of the flashing. The clamps 65 E are then engaged with the respective

brackets and the clamp screws H forced against the clamps adjacent their upper ends, thereby oscillating them so as to cause them to force the pliable apron of the flashing against the underlying portion of the 70 roofing material so as to tightly clamp the same between the backing and apron of the flashing.

From the foregoing description it will be observed that I have invented an improved 75 flashing for roofing construction which though simple in construction and convenient in use will produce a permanent watertight joint between the roof and upwardly projecting walls of all characters, and that the union between the roofing material and upwardly projecting walls affected by the use of my improved flashing will be permanent in character owing to the absence of sharp bends in the roofing material and to the absence of any tearing or perforation 80 of the roofing material in securing flashing thereto.

I claim:

1. A roof flashing comprising a backing, and a pliable apron between which and the backing the roofing material is adapted to be inserted. 90
2. A roof flashing comprising a backing, and a lead apron between which and the backing the roofing material is adapted to be inserted. 95
3. A roof flashing comprising a stiff backing, and a pliable apron secured adjacent the upper edge of said backing, the roofing 100 material being adapted to be inserted between the backing and apron.
4. A roof flashing comprising a horizontal portion adapted to be inserted between adjacent rows of bricks, and a depending vertical portion, said flashing being composed of a stiff backing and a pliable apron secured to the backing adjacent its upper edge and between which and the backing the roofing material is adapted to be inserted. 105
5. In a roof flashing, the combination with a backing, of a pliable apron secured to said backing and between which and said backing the roofing material is adapted to be inserted, and a clamp engaging said apron 110 to force the same into close engagement with the inserted roofing material.
6. The combination with a roof, of a wall projecting above the roof, a flashing comprising a backing and an apron between 115 which the edge of the roofing material is inserted, and a clamp supported upon the wall and depending over and engaging the flashing. 120
7. The combination with a roof, of a wall projecting above the roof, a flashing comprising a backing and an apron between which the edge of the roofing material is inserted, a bracket supported by the wall 125 and projecting above said flashing, a clamp 130

depending from said bracket and overlying the flashing, and means for forcing said clamp against the flashing to grip the roofing material between the backing and apron 5 of the flashing.

8. The combination with a roof, of a wall projecting above the roof, a flashing comprising a horizontal portion adapted to be inserted between adjacent rows of brick and 10 a depending vertical portion, said flashing being composed of a stiff backing and a pliable apron between which the edge of the roofing material is inserted, a plurality of

horizontal brackets secured to the horizontal portion of the flashing, clamps depending 15 from said brackets and overlying the vertical portion of the flashing, and means for forcing said clamps against the flashing to tightly secure the roofing material therein.

In testimony whereof, I have subscribed my name.

EWING M. FORBES.
